ROLLIN H. WHITE, OF CLEVELAND HEIGHTS, OHIO, ASSIGNOR TO THE CLEVELAND TRACTOR COMPANY, OF EUCLID, OHIO, A CORPORATION OF OHIO.

TRACK BELT AND UNIT THEREFOR.

Application filed July 17, 1920. Serial No. 396,955.

To all whom it may concern:

Be it known that I, ROLLIN H. WHITE, a citizen of the United States, residing at Cleveland Heights, in the county of Cuyahoga and State of Ohio, have invented a certain new and useful Improvement in Track Belts and Units Therefor, of which the following is a full, clear, and exact description.

10 The object of this invention is to produce, from suitable pressed steel links or units, track belts capable of being advantageously used as parts of track laying tractors.

15 The invention consists in the links or units substantially as hereinafter described and in the described combination of these units to form a track belt.

20 In the drawing, Fig. 1 is a top plan view of two pivoted together track belt units constructed according to this invention; Fig. 2 is a side elevation of said two track belt units; Fig. 3 is a front end view of one of said units; Fig. 4 is a vertical longitudinal sectional view in the plane of line 4—4 of Fig. 1; Fig. 5 is a sectional rear end view thereof, the section being in the plane of line 5—5 on Fig. 1; Fig. 6 is a sectional side elevation in the plane of line 6—6 on Fig. 1; Fig. 7 is a sectional end elevation in the plane of line 7—7 on Fig. 1.

25 Each unit is made of two pieces of pressed metal, to wit, a bottom plate 10, and a rail member 20, which is secured upon the bottom plate. And a track belt consists of a plurality of these units, the pins by which they are pivotally connected, and, preferably also, certain rollers which rotatably embrace certain outwardly projecting sleeves at the front ends of the track belt units, 30 which sleeves are so located that they may be engaged by the teeth of the double sprocket.

35 The bottom plate 10 has preferably its front end bent downwardly to form the ground gripping grouser 12. In the completed unit this bottom plate inclines upward very slightly with respect to the horizontal from the front to the rear end thereof, so that it may overlap the front edge of 40 the bottom plate of the link behind it.

45 The rail member 20 is formed from a flat blank of sheet metal so shaped and bent as to have the integral parts now to be specified. The middle part of the blank between

55 the front and rear ends thereof serves as a rail plate 23 for the track wheels carried by the tractor to run on (these track wheels, being shown by dotted lines in Fig. 2). Along the sides of this rail plate are longitudinally extended upwardly bent ribs 24 60 whose outer edges are extended downward in parallel vertical positions to form the rail sides 21. The lower edges of these rail sides are secured to the bottom plate 10 in any suitable way, but preferably by means of 65 downwardly projecting lugs 22 which go through holes in the bottom plate and have their downwardly projecting lower ends upset against the lower face of said bottom plate. At the rear end of each rail plate and 70 below the same, is a transversely extended sleeve 25,—which is produced by bending a tongue which is integral with and extends rearward from the rail plate. This tongue is bent downward and forward and upward 75 again into contact with the lower face of the rail plate, to which it is secured by welding or other suitable means. The lower part of this sleeve rests upon, and is secured to the bottom plate 10 by means of an integral lug 80 26 which is pressed out from the metal of which the sleeve is formed, and is passed through the hole in the bottom plate, and has its lower end upset against said bottom plate. This sleeve 25 forms an effective support for the rear end of the rail plate 23, and 85 it also embraces and fits tightly a spacing sleeve 31, whose length is substantially equal to the distance between the two rail sides.

90 The downturned rail sides 21 of the rail member project in front of the rail plate 23 in the form of ears 27. Each of these ears is formed with an integral outwardly projecting tubular cylindrical boss 28, said bosses being in axial alignment with each 95 other, and being produced by drawing the metal outward into the form shown.

99 To pivot together two of these links, in the process of forming a track belt, the sleeve 25 at the rear end of one link containing the spacing sleeve 31, is passed between the two ears 27 at the front end of the next link, and said sleeve is brought into axial alignment with the two tubular lugs 28. A pivot pin 40 is then passed endwise through 100 one of the tubular lugs 28 at the front end of one of the units, then through the sleeves 25 and 31 at the rear end of the other unit,

and then through the opposite tubular boss 28 at the front end of the first named unit.

33—33 represent two rollers which are rotatably mounted upon the two tubular bosses 28. 34—34 represent washers which embrace the pin 40 and overlap the ends of these rollers 33; and 35 represents cotter pins which are passed through pin 40 so that the projecting ends thereof will hold 10 the washers on the pin.

It is to be noted that there is a hole 37 formed through the upper wall of each sleeve 25. Also that the rail member 23 has at its front end a forwardly projecting 15 tongue 38 of such width that it may pass through and fit loosely in the hole 37 through the sleeve of the adjacent unit, and this tongue at its front end is curved down so as to engage and follow the curvature of 20 the sleeve. These tongues aid in providing a track belt formed of the described units with a substantially continuous track surface for the track wheels of the tractor to roll upon.

25 There will be used with a track belt formed of units which are constructed and connected as described a double sprocket, i. e., a sprocket having two circumferential rows of teeth, said rows being separated 30 such a distance that one set of teeth will engage one of the rollers 33 while the other set of teeth will engage the other rollers 33. The track wheels (shown in dotted lines on Fig. 2) mounted on the tractor 35 will engage and be supported by the rail plates 23, and will be guided so that their engagement with these rail plates will be maintained by the upwardly extended longitudinal ribs 24 at the sides of the rail plate.

40 It is to be understood that although the described means for connecting together the rail member and the bottom plate are those which are preferred, nevertheless these 45 parts may be connected together in the described relation to each other by any other means suitable for the purpose. The construction shown in the drawing is the best form known to me in which the invention 50 may be embodied; but it is not desired that the claims be limited to this precise construction, except to the extent plainly expressed therein.

Having described my invention, I claim:

55 1. A pressed metal track belt comprising a bottom plate and a rail member formed from a single blank having substantially vertical side members with rounded ribs at their upper edges having spaced, double 60 thick walls and a depressed longitudinal plate portion between the inner walls of

said ribs, the lower edges of the side members being secured to the bottom plate.

2. A track belt unit comprising, in combination, a bottom plate and a rail member 65 secured thereon said rail member having a centrally disposed longitudinally extended rail plate and downwardly extended integral rail sides which are spaced apart 70 and which engage with and are secured to the bottom plate; said rail member having at its rear end an integral sleeve which rests upon and is secured to the bottom plate, and the rail sides of the rail member being extended forward in the form of 75 ears, and said ears having outwardly extended integral cylindrical tubular lugs which are disposed in transverse alignment, and rollers rotatably mounted upon said lugs.

3. A track belt unit comprising, a combination, a bottom plate and a rail member 85 secured thereon said rail member having a centrally disposed longitudinally extended rail plate and downwardly extended integral rail sides which are spaced apart 90 and which engage with and are secured to the bottom plate, said rail member having at its rear end an integral sleeve which rests upon and is secured to the bottom plate, and the rail sides of the rail member being extended forward in the form of ears, and said rail member along its sides having upwardly pressed longitudinally extended 95 ribs.

4. A track belt made up of a plurality of pivoted together units each comprising a shoe and a rail member, said rail member comprising downwardly extending side portions which are secured to said shoe, an elevated longitudinally extending track plate which has a notch at one end and a tongue at the other end, and ears extending from one end of the ends of the side portions of the rail members, the said tongue lying intermediate said ears and extended into the notch in the track plate of the adjacent unit.

5. A track belt unit comprising a bottom plate, and a rail member secured thereto, 110 said rail member being formed of a single sheet of pressed metal bent to form a substantially horizontal rail plate having roller guide ribs bent up longitudinally therefrom, and rail sides depending from the upper end of said ribs and secured to said bottom plate to support the rail member thereon.

In testimony whereof, I hereunto affix my signature.

ROLLIN H. WHITE.
